CLAIM

The ornamental design for a speaker as shown and described.

DESCRIPTION

FIG. 1 is a front top perspective view of a speaker showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

On the front face, the broken line and unshaded region therein forms no part of the claimed design. On the top surface, the circular broken line and unshaded region therein forms no part of the claimed design. On the rear face, the rectangular broken line region and the broken lines and unshaded region therein forms no part of the claimed design. The broken lines and unshaded regions bottom forming the bottom region forms no part of the claimed design.

1 Claim, 8 Drawing Sheets
